CLAIM

The ornamental design for a self-supporting foldable flashlight-tool combination, as shown and described.

DESCRIPTION

FIG. 1 is a perspective view of the self-supporting foldable flashlight-tool combination in a partially unfolded configuration.

FIG. 2 is an another perspective view thereof.

FIG. 3 is a top view thereof.

FIG. 4 is a side view thereof.

FIG. 5 is a front view thereof.

FIG. 6 is a rear view thereof.

FIG. 7 is a bottom view thereof.

FIG. 8 is a third perspective view thereof in a folded configuration; and,

FIG. 9 is a side view thereof.

The broken line showing of the other parts are for illustrative purposes only and forms no part of the claimed design.
